CLAIM

The ornamental design for a mammography machine, as shown and described.

DESCRIPTION

FIG. 1 is a front view of a mammography machine embodying the new design;

FIG. 2 is a back view thereof;

FIG. 3 is a side view thereof;

FIG. 4 is another side view thereof;

FIG. 5 is a top view thereof;

FIG. 6 is a bottom view thereof;

FIG. 7 is a perspective view thereof;

FIG. 8 is another perspective view thereof;

FIG. 9 is another perspective view thereof;

FIG. 10 is another perspective view thereof;

FIG. 11 is another perspective view thereof;

FIG. 12 is another perspective view thereof;

FIG. 13 is another perspective view thereof;

FIG. 14 is another perspective view thereof;

FIG. 15 is another perspective view thereof;

FIG. 16 is another perspective thereof showing a radiation source and an image sensor of the mammography machine moved to an alternative position;

FIG. 17 is another perspective thereof showing the radiation source and the image sensor of the mammography machine moved to an alternative position;

FIG. 18 is another perspective thereof showing the radiation source and the image sensor of the mammography machine moved to an alternative position;

FIG. 19 is another perspective thereof showing the radiation source and the image sensor of the mammography machine moved to an alternative position;

FIG. 20 is an enlarged perspective view of a portion of the mammography machine; and,

(Continued)

FIG. 21 is an enlarged perspective view of a portion of the mammography machine.

The broken lines illustrate portions of the mammography machine that form no part of the claimed design.

1 Claim, 21 Drawing Sheets
